ELECTRODE HOLDER AND CONTACT MEANS

Charles Gordon Heys Hallett, London, England,
assignor to The Morgan Crucible Company
Limited, London, England, a company of Great
Britain

Application June 3, 1946, Serial No. 673,967
In Great Britain January 19, 1945

10 Claims. (Cl. 314—129)

1
This invention relates to improvements in the contacts which carry the current into the electrodes in arc lamps, electric welding machines and the like.

One form of contact normally used for carrying the current into the arc lamp carbons consists of rectangular metal blocks which slide in rectangular slots in the carbon holder and press radially onto the side of the carbon. Either one or two blocks are commonly used. When one block is used it forces the carbon against the side of the holder from which it receives the majority of the current. In some cases the contact blocks are fitted with copper leads to convey the current, but in other cases they are used merely as pressure blocks.

The above mentioned arrangement has proved suitable for normal currents, e. g. of the order of 150 amps, but they are not capable of dealing with exceptionally heavy currents. For normal currents it is normally necessary to employ some special metal, such as Monel metal, which will not readily oxidize. The contacts become very much heated because the resistance of the carbon electrode is high and considerable heat is generated by the passage of the current. The contact between the rectangular block and the slot in which it slides is poor, and at heavy currents the cooling of the contact block presents a very difficult problem.

The improvement according to the present invention overcomes the difficulties outlined above, and provides an arrangement which can be used satisfactorily with very high current densities which may be six or more times those normally used, and which I can produce with a "wind drawn" arc, i. e. an arc along which a high-velocity air blast is blown and drawn away.

The arrangement according to the invention ensures that the contact between the contact block and the electrode holder is of the same quality as that between the contact block and the electrode.

In accordance with the invention a contact block for an electrode of an arc lamp and the like has a wedge form coacting with a sloping surface of the electrode holder, so that an axial thrust causes it to bear with pressure upon that surface and upon the electrode. Preferably there is a plurality of such contact blocks arranged around the electrode. The contact block, or plurality thereof, is mounted in the holder with axial displaceability, to the extent required to produce the wedge action, and under yielding or spring pressure in the axial direction.

2

An ordinary simple form of wedge may be employed in the construction of the contact block but the angle of such wedge will require careful selection. If the angle is too acute the wedge may be liable to jam, whereas if the wedge angle is increased to, say, 60°, to make jamming impossible, the wedge may be inconveniently large and difficult to make stable.

This difficulty may be overcome, according to a preferred feature of the invention, by constructing the contact block as a series of wedge elements, one behind the other, the electrode holder being formed with a corresponding series of coacting sloping surfaces. The wedge elements of the series are preferably formed as an integral unit. In effect, therefore, the back of the contact block, i. e. the face opposite that which bears on the electrode, has a serrated formation, and the surface of the electrode holder is correspondingly serrated. The back of the contact block may be plane, except for serrations transverse to its length forming a series of wedge faces, or, alternatively, it may be of cylindrical or conical form, coaxial with the axis of the electrode and serrated with circular, or substantially circular, grooves.

This latter case may be developed to produce a most practical and useful form of contact block when there is a plurality of contact blocks surrounding the electrode. This consists in forming the several surfaces of the wedge elements of the several blocks so as substantially to produce a helical formation matching a helical thread in the electrode holder. The contact blocks may accordingly be severally produced by dividing a bolt along its length into segmental jaws. The bolt may be screw-threaded externally to match an internal screw-thread in the electrode holder and may be centrally bored to accommodate the electrode, preferably to the precise diameter of the electrode. Each segmental jaw constitutes a contact block and the assembly of the several complementary blocks is screwed into the thread hole in the electrode holder. The material cut or sawed away from the bolt when dividing it into segments permits the gripping of the segmental jaws upon the electrode whilst slackness of fit in the threaded electrode holder provides the necessary freedom of movement of the segmental jaws in the electrode holder to allow the wedging action to function.

The employment of contacts in the form of wedges may require that the friction between the electrode and the wedge or wedges should be taken into account in order that there shall not

be an undue variation of the pressure of the wedge contact upon the surfaces that it engages, having regard to the external pressure due to friction when the electrode is fed forward, and the reduction of pressure when the electrode is retracted, e. g. on account of overfeeding.

Therefore, according to a further feature of the invention, the electrode feeding means may be mounted and arranged so that the reaction force thereon from the electrode is transmitted to counteract axial thrust on the contact block or blocks due to friction between the same and the electrode being fed. The electrode feeding means may therefore be mounted on a floating support or carriage opposing, when it is rearwardly urged as the feeding means drives the electrode forward, spring pressure or other yielding axial thrust transmitted to the contact block or blocks. The floating support or carriage may accordingly be the intermediary through which the yielding axial thrust is transmitted.

With such an arrangement, when the electrode is fed forward its frictional forward urge on the wedge contact or contacts is counteracted by a rearward reactive force from the electrode driving means. In this way the contact pressure is maintained substantially constant at the pressure due to that which is imposed upon it by, for example, a compression spring or springs bearing thereon, despite changes of friction.

The invention is illustrated, by way of example, in the accompanying drawings, in which:

Figure 1 is a diagrammatic sectional elevation illustrative of the principle underlying the invention;

Figure 2 is a section on the line 2—2 of Figure 1;

Figure 3 is a diagrammatic sectional elevation showing a slight modification of Figure 1;

Figure 4 is a section on the line 4—4 of Figure 3;

Figure 5 is a section on the line 5—5 of Figures 1 and 3;

Figure 6 shows a modification of a detail of Figure 1 or 3, in sectional elevation;

Figure 7 and Figure 8 are alternative sections taken on the line 7, 8—7, 8 of Figure 6.

Figure 9 is a sectional elevation of a practical form of construction according to the invention;

Figure 10 is a horizontal central section of a part of Figure 9;

Figure 11 is a section taken on the line 11—11 of Figure 9;

Figure 12 is a section taken on the line 12—12 of Figure 9.

Figure 13 is an end view of a detail of Figure 9;

Figure 14 is a detail in section to an enlarged scale.

Referring to Figures 1, 2 and 5 of the drawings, 1 is the electrode holder, 2 the electrode and 3 a contact block. 4 is a toothed feeding wheel in driving engagement with the electrode 2. This feed wheel is mounted on a bush 5 secured to a spindle 6 on one end of which is mounted a worm wheel 7 driven by a worm 8. The worm 8 is carried by a spindle 9 mounted, as shown, in brackets 10 projecting from the casing of the electrode holder 1. A tension spring 11 connected to the spindle 6 urges the feed wheel 4 into driving engagement with the electrode 2.

The spindle 6 is rotatably mounted in a double or forked link 12, the forward end of which is pivotally connected with the contact block 3, and the rearward end of which is connected by a

compression spring 13 to a lug 14 projecting from the casing of the electrode holder.

It will be seen that the main axial thrust upon the contact block 3 is transmitted from the spring 13 through the intermediary of the link 12 supporting the driving means, and that when the drive has come into operation the rearward reaction force exerted on the feed wheel 4, due to its driving engagement with the electrode 2, and the amount of which is dependent on the friction between the contact block 3 and the electrode 2, is opposed to the thrust from the spring 13, and accordingly relieves the contact block 3 of excessive thrust which might cause jamming and which, in effect, maintains the friction between the electrode and the contact block substantially constant.

It will also be noted that an equally good contact is produced as between the contact block and the electrode holder as between the contact block and the electrode, so that not only is there established the proper electrical connection between the electrode holder and the electrode (the electrode holder being connected to the electrical supply), but there is ensured a good thermal contact between the contact block and the electrode holder to carry away from the contact block the great heat to which it is subjected and transfer it to the electrode holder which will normally be watercooled. Due to the satisfactory thermal contact which is established according to the invention between the contact block and the electrode holder there may be employed much larger currents than have hitherto been possible.

Figures 3 and 4 differ from Figures 1 and 2 in that the worm 8 is mounted in bearings carried by the link 12 instead of being carried in brackets extending from the electrode holder. Accordingly in this case the driving thrust of the worm 8 on the worm wheel 7 does not react in opposition to the spring 13 as it does in the construction illustrated by Figures 1 and 2. In this connection, referring back to Figures 1 and 2, it may be arranged by mounting the worm 8 on an inclination to the horizontal, that the worm thrust on the worm wheel 7 augments the force exerted by the spring 11 to press the feed wheel 4 upon the electrode 2 so that when the friction between the electrode of the contact block increases, the pressure of the feed wheel on the electrode will likewise increase and so prevent slipping.

It will be appreciated that other means of drive to the feed wheel may be employed. For instance, in the case shown in Figures 1 and 2 there may be employed a bevel wheeled drive whilst in the case of Figures 3 and 4 the drive may be by bevel wheels or may be transmitted direct to the spindle of the feed wheel by means of a flexible shaft.

Figure 6 illustrates a contact block which is serrated so as to produce a series of wedge elements as hereinbefore referred to. The contact block 3 is formed with serrations 15 which loosely fit into corresponding serrations 16 in the electrode holder 1. It will be seen that this construction is equivalent to a single ordinary wedge with a large slope, but accommodated in a much smaller space.

Figure 7 shows one form of section of the contact block 3 having in this case a straight back which would be located in a rectangular recess in the electrode holder 1.

Figure 8, on the other hand, shows an alternative section illustrating the provision of three

serrated contact blocks forming complementarily a cylindrical section accommodated in a circular bore in the electrode holder 1. In the practical form of construction about to be described the complementary segmental form of contact block is employed.

It will be appreciated in regard to the diagrammatic forms shown in Figures 1 to 7 that although only one contact block is shown as bearing on the electrode, there may be disposed two or more, preferably three, such contact blocks at equal angular spacings around the electrode.

Referring now to Figures 9 to 12, the electrode holder casing is indicated at 20 and within this is mounted the electrode feeding means whilst the contact blocks, which will be described hereafter, are mounted in a detachable nose piece 21; the electrode is indicated by the reference numeral 22.

The drive for the electrode feeding means is from a shaft 23 which drives, through gears 24, 25, an articulated shaft 26 having a forward bearing at 27. In front of the bearing 27 the shaft carries a worm 28. This worm 28 drives (see Figure 11) a pair of worm wheels 29, 30. These worm wheels are splined on spindles on which, respectively, are splined electrode feed wheels 31, 32. The feed wheels 31, 32, each have two toothed elements 33, 33, and 34, 34, which engage the electrode 22. The spindles of the respective feed wheels 31, 32, are carried by frames 35, 36, pivoted at 37, 38, and urged to press the feed wheels upon the electrode by compression springs 39, 40.

The contact blocks (see Figure 13) are complementary segments 41 of a cylindrical bolt which is threaded at 42 and screwed into the bore of the electrode holder nose piece 21 which is threaded as shown at 43. Figure 14 shows the matching thread forms of one of the contact segments 41 and the electrode holder 21 and illustrates the wedging action. The wedge slope in this case is 57½°.

The rear ends of the contact block segments 41 are formed as shown in Figures 9 and 13 with projections 44. These projections serve as gimbals engaging recess 45 in a ring 46 mounted at the head of a carriage structure 47 which supports the electrode feeding means hereinbefore described. The carriage structure 47 at its rear end is slidably mounted on a tube 48 and is thus a floating carriage. A main compression spring 49 is interposed between a shoulder on the carriage 47 and a rear cap 50 and thus serves to exert, through the intermediary of the carriage 47, an axial thrust upon the contact block segments 41, bringing the wedge action into play and causing the contact block segments 41 to bear upon the electrode and the sloping surfaces of the teeth 42 of the contact blocks to bear with like pressure upon the sloping surfaces of the teeth 43 of the electrode holder as has hereinbefore been explained. The reaction thrust from the drive between the feed wheels 33, 34, and the electrode will be rearwardly transmitted by the carriage 47 to oppose the force of the spring 49, thus maintaining the wedge pressure substantially constant notwithstanding changes of friction between the contact block segments 41 and the electrode 22.

The part marked 51 in Figure 9 is a trip lever having a nose 52 bearing on the electrode 22 and a tail carrying a contact 53 cooperating with a contact 54 and coming into engagement therewith when the tail end of the electrode 22, in the course of consumption, passes beyond the nose 52, the spring 55 then causing the lever 51 to trip.

The contacts 53, 54 may be connected in an electrical circuit adapted, when closed, to give an indication showing that the electrode has been nearly consumed.

5 It will be seen from Figure 9 that the electrode holder nose piece 21 has passages 56 for the circulation of cooling water which is supplied at the union marked 57 and discharged through a similar union not seen in the drawing. Due to the 10 good thermal contact between the contact block segments and the electrode holder the very great heat developed in the contact block segments, especially when large currents for which the present device is adapted are employed, is dissipated 15 by transfer to the water cooled electrode holder 21.

What I claim is:

1. The combination of an electrode, an electrode holder, and at least one contact block interposed between the electrode and electrode holder, the contact block comprising a series of wedge elements, one behind another, and the electrode holder being formed with a corresponding series of coacting surfaces.

2. The combination of an electrode, an electrode holder, and at least one contact block interposed between the electrode and electrode holder, the contact block comprising an integral series of wedge elements, one behind another, and the electrode holder being formed with a corresponding series of coacting surfaces.

3. The combination of an electrode, an electrode holder, and a plurality of complementary contact blocks surrounding the electrode and interposed between the electrode and the electrode holder, each contact block having a series of surfaces sloping towards the electrodes which in the assembly of contact blocks produce a helical formation and the electrode holder having a helical thread matching said helical formation.

4. The combination of an electrode, an electrode holder, a plurality of complementary contact blocks surrounding the electrode and interposed between the electrode and the electrode holder, each contact block having a series of surfaces sloping towards the electrode which in the assembly of contact blocks produce a helical formation and the electrode holder having a helical thread matching said helical formation, and means for applying an axial thrust to the contact blocks.

5. The combination of an electrode, an electrode holder, electrode feeding means, at least one contact block interposed between the electrode and electrode holder, the contact block and the electrode holder having engaging surfaces sloping towards the electrode, means for applying an axial thrust to the contact block, and a connection between said means and said electrode feeding means for transmitting reaction upon the latter by the electrode to oppose the said axial thrust.

6. In an arc lamp or the like the combination of an electrode, an electrode holder, electrode feeding means, at least one contact block interposed between the electrode and electrode holder, the contact block and the electrode holder having engaging surfaces sloping towards the electrode, means for applying an axial thrust to the contact block, a floating support for the electrode feeding means, and means connecting said floating support with the said means which applies the axial thrust.

7. In an arc lamp or the like the combination of an electrode, an electrode holder, electrode

feeding means, at least one contact block interposed between the electrode and electrode holder, the contact block and the electrode holder having engaging surfaces sloping towards the electrode, a floating support for the electrode feeding means, and means applying axial thrust to the contact block through the intermediary of the floating support.

8. In an arc lamp or the like the combination of an electrode, an electrode holder, electrode feeding means, at least one contact block interposed between the electrode and electrode holder, the contact block and the electrode holder having engaging surfaces sloping towards the electrode, a floating support for the electrode feeding means, and spring means applying axial thrust to the contact block through the intermediary of the floating support.

9. The combination of an electrode, an electrode holder, and at least one contact block interposed between the electrode and electrode holder, the contact block having a longitudinally grooved electrode engaging surface on one side and a series of longitudinally spaced wedge elements on its opposite side, said wedge elements being

adapted to coact with a corresponding series of wedge surfaces on said electrode holder.

10. The combination of an electrode, an electrode holder, and a plurality of complementary contact blocks surrounding the electrode and interposed between the electrode and the electrode holder, each contact block having a longitudinally grooved electrode engaging surface on one side and a series of longitudinally spaced wedge surfaces sloping toward the electrode on its opposite side, said contact blocks when assembled, producing a helical formation, and the electrode holder having a helical thread, matching said helical formation and adapted to coact therewith.
